A water cooler or drinking fountain is a device for cooling water and dispensing it in cups or glasses. It is often used in office buildings, restaurants, and other places where there is a large number of people. It is a common occurrence for a water cooler to overflow, causing damage to the building and its furnishings and equipment. This is particularly true in high office buildings where surges of excessive pressure are likely to be encountered in the water piping system. Fatigue failure of metallic parts in the presence of vibration may result, such vibration being caused either by the water cooler itself or by adjacent machinery. Failure of the temperature controls of the water cooler may cause freezing, in which case bursting of tanks, piping or fittings due to such freezing is likely to result.

Failures of the character mentioned which have resulted in overflow of water coolers have

led to loss of property and damage to the building. It is the object of the present invention to provide a protective device for water coolers which will prevent damage to the building and its furnishings and equipment due to flooding from a water cooler.

UNITED STATES PATENT OFFICE

WATER COOLER PROTECTIVE SYSTEM

Joseph Gray Jackson, Bala Cynwyd, Pa., assignor to Sunroc Refrigeration Company, Dover, Del., a corporation of Delaware

Application July 20, 1948, Serial No. 39,787

6 Claims. (Cl. 62—7)

1

My invention relates to protective devices for water coolers.

A purpose of the invention is to avoid damage to a building and its furnishings and equipment due to flooding from a water cooler.

A further purpose is to cut off flow of water in a water cooler whenever an electric circuit is completed between protective contacts in a catch basin below the water-holding portion of the cooler.

A further purpose is to provide a normally open solenoid valve in an inlet pressure line to a water cooler, and to close the valve whenever sensing elements indicate overflow of water.

Further purposes appear in the specification and in the claims.

In the drawings I have chosen to illustrate a few only of the numerous embodiments in which my invention may appear, choosing the forms shown from the standpoints of convenience in illustration, satisfactory operation and clear demonstration of the principles involved.

Figure 1 is a side elevation, largely diagrammatic, of a water cooler to which my invention has been applied.

Figure 2 is a fragmentary transverse section across the sensing contacts in the drip basin.

Figure 3 is a circuit diagram.

Figure 4 is a circuit diagram showing a variation.

Describing in illustration but not in limitation and referring to the drawings:

Especially in large office buildings and in industrial plants employing complicated machinery, havoc has been wrought from time to time when something has gone wrong with a water cooler or drinking fountain so as to cause it to overflow. Bursting or other failure of a mechanically refrigerated water cooler can occur from a number of causes. Metallic or fabrication defects can cause piping, tanks or fittings to leak. Pressure can cause bursting of components. This is especially likely to occur in high office buildings, where surges of excessive pressure are likely to be encountered in the water piping system. Fatigue failure of metallic parts in the presence of vibration may result, such vibration being caused either by the water cooler itself or by adjacent machinery. Failure of the temperature controls of the water cooler may cause freezing, in which case bursting of tanks, piping or fittings due to such freezing is likely to result.

been sufficiently frequent in some localities so that city ordinances or regulations of individual companies or buildings have restricted the use of water coolers and drinking fountains connected to pressure water sources.

The present invention is designed to reduce or eliminate the difficulty from flooding in case a water cooler overflows from any cause, and particularly to restrict the amount of water available to cause damage by preventing flow of additional water into the system until the failure is corrected.

As shown in the drawings, a conventional water cooler or drinking fountain is illustrated, comprising a cabinet 20, suitably of rectangular form, and including a water storage compartment 21 at one side of the top, a food storage compartment 22 at the other side of the top, separated from the water storage compartment by a suitable metallic partition 23, and a mechanical compartment 24 in the lower portion separated from the water and food storage compartments by a partition 25. Suitable heat insulation, not shown, is usually employed.

25 The water system includes a pressure connection 26 to a public drinking water system, feeding into a safety valve 27, which is normally open as later explained, and then through a float valve 28 controlled by a float 29 and thence discharging into the water storage tank. When a suitable level is reached in the water storage tank, introduction of water is cut off by closing of the float valve as well known.

35 Discharge of water from the water storage tank is accomplished through a pipe 30 to a dispenser 31, here shown as a faucet, rather than a bubbler which is sometimes used. Waste water is received by a catch basin 32. A downwardly directed portion 33 of the pipe 30 below the faucet prevents complete emptying of the water storage compartment under normal operation, so that sufficient water remains to function as a sweet water bath to aid in cooling incoming water.

45 The mechanical refrigeration system may be of any suitable type, here shown as a hermetic motor-compressor unit 34 supported on a cross rib 35 of the cabinet. High pressure refrigerant such as freon passes through a pipe 36 to a static air condenser 37 contained in a vertical air flue 38. From the condenser the refrigerant passes through a constrictor 39, which may be an expansion valve or capillary tube, to an evaporator or cooling unit 40, conveniently located in the food compartment. Cooling of the water is ac-

complished by heat conduction from the water storage compartment. Ice cube trays 42 are conveniently provided in the food compartment. From the evaporator the refrigerant returns to the suction side of the compressor through a pipe 43.

Suitably located at any convenient point below the water carrying parts of the equipment and desirably extending out fully to the outside of the cabinet so that it will catch water overflowing due to bursting of pipes, fittings or tanks, is a drip basin 44 sloping downwardly from the outer edges to a sump 45 which preferably constitutes the lowest point of the drip basin. Conveniently located in the sump are sensing elements 46, suitably in the form of metallic contact buttons mounted on insulating bushings 48 and spaced at 49 by a small distance which is sufficient to assure that no current will flow under the low voltage when the sump is dry, but which will permit flow of current when the sump fills with water from any cause.

The normally open valve 27 comprises a valve element 50 cooperating with a valve seat 51 and having a valve stem 52. A spring abutment 53 on the valve stem is urged by a spring 54 to the open position of the valve, so that the safety valve normally remains open. A solenoid 55 operates on an armature 56 on the valve stem, to close the valve when the solenoid is energized. The solenoid 55 is in series with a relay switch 57 across a suitable source of electric current 58 such as a commercial alternating current source at 110 volts and 60 cycles. The relay is normally open and is biased toward opening by a suitable spring not shown. The primary 59 of a step down transformer is also connected across the line and a low voltage secondary 60 of the transformer is in series with the sensing contacts 46 and 47 and the electromagnetic winding 61 of the relay. The thermostatic control element 62 of the refrigeration equipment, suitably of the expanding and contracting liquid type, controls a bellows 63 which on expansion closes a switch 64 in series with the motor 34' of the hermetic motor-compressor unit, across the line.

In operation the protective device does not function unless some abnormal condition causes water to collect in the sump. When this condition develops, the secondary circuit of the transformer is completed through the contacts and the relay is energized to close the relay switch 57, thus energizing the solenoid to cause the solenoid valve 27 to close, thus cutting off the flow of water from the pressure source. As long as water remains in the sump, the flow will be cut off, but whenever the difficulty has been corrected and the water removed from the sump, the relay will open and the solenoid valve will accordingly open and permit normal functioning of the water system.

It will thus be evident that even in case of a freeze-up and bursting of the water storage tank the maximum amount of water available to cause damage is the water present in the tank and associated piping.

In case there is danger that water will be discharged externally and may not affect the protective system quickly enough, suitable openings or louvers 65 are provided in the cabinet to assure that water leaking down the sides of the cabinet will enter the interior and affect the protective system.

In some cases where a solenoid valve is being employed for another purpose, as to control the admission of water into the water cooler under

the regulation of a liquid level device such as a float switch, it may be desirable to employ the same solenoid valve as a safety device in accordance with the present invention. Figure 4 illustrates a circuit diagram for a mechanism of this character. In this instance the safety valve 27' is normally closed, the valve element 50' being urged toward closing position by a spring 54' surrounding the valve stem 52. The valve seat 51' is reversed with respect to the valve seat in Figure 3.

In this case the low voltage secondary 60 of the transformer is connected in series with the solenoid 55, which is also in series with a float switch 66 operating from a float 67 in the water storage compartment 21, thus eliminating the necessity for the float valve 28 in this form. The sensing elements 46 are suitably shunted across the solenoid.

Thus in operation when the water level falls the float 67 falls and closes the float switch 66 which under normal operating conditions will cause current to pass through the solenoid 55 and open the solenoid valve against the action of the spring 54' for a time long enough to fill the water storage compartment and permit the float switch to again open. As soon as the float switch opens the valve 27' returns to its normally closed condition. In case an emergency condition develops, water will short circuit the gap between the sensing elements 46, thus shunting the solenoid 55. Accordingly even though the float 67 may fall due to the leakage of water from the water storage compartment, and even though the float switch 66 may close, the solenoid valve will remain closed since the solenoid is shunted by the sensing elements. Thus it is not possible for the float switch to cause water to enter through the solenoid valve as long as the emergency condition continues. Whenever the emergency is corrected and water is removed from between the sensing elements, the water cooler can function in the normal manner.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention, what I claim as new and desire to secure by Letters Patent is:

- 55 1. In a water cooler, a refrigerated dispensing unit having a connection to a source of water, a valve in the connection, an operating solenoid for the valve, a catch basin below the dispensing unit, spaced contacts in communication with the basin,
- 60 a source of current connected to the contacts, and electrical means in circuit with the solenoid, the contacts and the source of current for closing the valve when the presence of water between the contacts permits the current to flow.
- 65 2. In a water cooler, a refrigerated dispensing unit having a connection to a source of water, a normally open valve in the connection, a drip basin below the dispensing unit, spaced contacts in communication with the basin, a source of current connected to the contacts and electrical means interposed between the contacts and the source of current for closing the valve when the presence of water between the contacts permits the current to flow.
- 70 3. In a water cooler, a refrigerated dispensing

unit having a connection to a source of water, a valve in the connection, a solenoid for closing the valve, biasing means for maintaining the valve open, a drip basin below the dispensing unit, spaced contacts in communication with the basin, a source of current connected to the contacts, and electrical connections interposed between the contacts, the source of current and the solenoid for closing the valve when the presence of water between the contacts permits current to flow.

4. In a water cooler, a refrigerated dispensing unit having connection to a source of water, a valve in the connection, a solenoid operatively connected to the valve, a float switch, electrical means including a circuit for energizing the solenoid under normal conditions when the float switch closes, and spaced electric contact elements connected in the circuit, and adapted to permit current flow through water therebetween to render the electrical means inoperative when an emergency condition exists.

5. In a water cooler, a refrigerated dispensing unit having a connection to a source of water, a normally closed valve in the connection, a solenoid for opening the valve, electrical means including a circuit for energizing the solenoid at

intervals to admit water and spaced electric contact elements connected in the circuit, and adapted to permit current flow through water therebetween, to render the solenoid inoperative when an emergency condition exists.

6. In a water cooler, a refrigerated dispensing unit having a connection to a source of water, a normally closed valve in the connection, a solenoid for opening the valve, a water storage chamber connected to receive water from the valve, a float switch responding to the level of water in the chamber, electrical means for energizing the solenoid under normal conditions when the float switch is closed, a drip basin below the dispensing unit, and spaced contacts in communication with the drip basin and electrically connected in shunt across the solenoid.
